UNITED STATES PATENT OFFICE.

DILLON F. HATCH, ROBERT H. JENKS, AND JOHN J. WEMPLE, OF CLEVELAND, OHIO.

DESIGN FOR A DOOR.

SPECIFICATION forming part of Design No. 21,073, dated September 29, 1891.

Application filed May 21, 1891. Serial No. 393,652. Term of patent 7 years.

To all whom it may concern:

Be it known that we, DILLON F. HATCH, ROBERT H. JENKS, and JOHN J. WEMPLE, all citizens of the United States, residing in Cleveland, county of Cuyahoga, and State of Ohio, have invented and produced a new and original Design for Doors, of which the following is a full specification, reference being had to the annexed drawing, forming part thereof.

The said door is for rooms, halls, closets, and other similar places in buildings or dwellings of various constructions, and especially for outside and vestibule doors.

The accompanying drawing represents a view of the door. On the view of the door is illustrated our design. For a description thereof reference will be had to the following specification.

A leading and essential feature of our design consists in two or more decorated panels A, having carved upon the projecting face thereof scroll leaf-work in quarterings with a central rosette a in relief, as shown in the drawing. Above these panels is a spiral or rope formed molding or piece B, extending

across the door between the side pieces C C of the door-frame. Under the window-stool of the door is a carved fret D, at the terminals of which are embellishing-blocks E E 30 under the base of the window. Below the window-cap F are decorations of a dentil configuration G. On each side of the window is a pilaster H, adorned with a cap and base having the semblance of a composite ornamentation, attached to the sides or stiles of the door-frame.

The entire contour of the figurate door presents a decorative and harmonizing effect.

What we claim as new in design for doors, 40 and desire to secure by Letters Patent, is—

The design for a door, as herein shown and described.

In testimony whereof we affix our signatures in presence of two witnesses.

DILLON F. HATCH.
ROBERT H. JENKS.
JOHN J. WEMPLE.
